UNITED STATES PATENT OFFICE.

JOHN MORCH AND ANTHONY MORCH, OF BROOKLYN, NEW YORK.

AUTOMATIC TORPEDO-GUARD.

1,249,170.

Specification of Letters Patent.

Patented Dec. 4, 1917.

Application filed February 24, 1917. Serial No. 150,761.

Be it known that we, JOHN MORCH and ANTHONY MORCH, citizens of the United States, residing at Brooklyn, in the county of Kings and State of New York, have invented new and useful Improvements in Automatic Torpedo-Guards, of which the following is a specification.

This invention relates to torpedo guards and is especially designed to provide means for protecting the sides of a ship from injury by deflecting torpedoes which may be directed against the hull of the ship regardless of the point from which such torpedoes are fired or in what direction they are traveling.

A further object is to provide a series of protecting guard members each comprising a unit mounted in a substantially vertical position and including a rigid member and a plurality of resiliently mounted buffers or buffering devices arranged to deflect a torpedo which is about to come into contact with the hull of the ship.

A further object is to construct a unit of the character specified, such units being mounted in parallel series, so that upon the engagement of one buffer by a torpedo, that buffer will be immediately thrown out of normal position, deflecting the torpedo, and will mechanically operate the other buffers, resiliently mounted, which will also be thrown out of normal position and will cause the torpedo to continue in the direction in which it has been deflected, or substantially in that direction, until further danger has passed.

A still further object is to provide certain novel mechanical construction especially adapted to carry out the purposes of the device as above set forth.

In the drawing forming part of this application;—

Figure 1 is a view in elevation showing a series of guards as applied to a portion of the side of a vessel.

Fig. 2 is a vertical transverse section through a portion of a ship's hull showing one of the units of the guard in side elevation.

Figs. 3, 4 and 5 illustrate the buffers in elevation with parts in section showing the mounting means.

Fig. 6 is a detail showing the action of

certain of the buffers and springs under impact and compression.

Referring to the drawings in detail, it may first be observed that a series of units, each including a plurality of buffering devices is arranged about the sides of the ship, such units extending from a point at or near the water line toward the keel. The length of the units may vary according to the type of vessel to be protected. The units each comprise a channel member 10, the flanges of which are provided with apertures 12 in which are mounted the buffers described below. Each channel member may have its flanges cut away near the ends as shown at 14 and these cut-away portions terminate at a point adjacent to an end member 15 which is apertured at 16 for the purpose of securing the leaf springs 20 of U-shape formation pivotally connected with adjacent buffering members. Each U-shape spring 20 is provided with ears 21 apertured for the purpose of receiving bolts 22 connected with an end member 15. Straps or clamps 24 are provided at the required points between the ends of the leaf springs for the purpose of retaining the leaf members in position.

Similar clamps or straps 24 are provided for connection with intermediate leaf springs 25 which springs likewise have ears formed thereon, the ears being designated 26 and being secured by bolts 27 to shank members 28 of buffers 30. Springs 20 have the ends thereof not already referred to connected by means of bolts 31 with shank members 28 in a similar manner. These shank members are recessed in the manner shown and provide for the accommodation of the springs above mentioned.

Buffers 30 of any suitable material are formed preferably in the manner shown or have substantially that configuration, having a cone-shaped top with a rounded surface and an enlarged base portion. The shank members are rigidly connected with buffers 30 and pivotal connection is effected at 34 with channel members 10 by means of transverse bolts passing through apertures in the flanges of the channel.

Each unit may include as many buffers as circumstances require, these devices being spaced at suitable distances to prevent a torpedo directed toward the ship from passing

between said buffers. The larger buffers 30 are properly spaced and between each pair is a smaller buffering device 35 mounted on leaf spring 25 and having pivotal connection therewith. If the torpedo strikes one of the smaller buffers first, the latter will be deflected and the spring 25 will be placed under tension causing movement to be transmitted to the adjacent buffers 30 in view of the pivotal connection with springs 25, and the torpedo will therefore be further deflected after having passed buffer 35 until its course is such that no further danger of injury to the ship will be possible. If the torpedo strikes the buffering device 35 at a different angle so that it is deflected toward the bow or stern of the ship the deflecting action will be continued by the buffering devices of the unit next adjacent.

The mounting of buffer 35 differs from that of buffer 30, which latter are pivotally secured between leaf springs 20 and 25, whereas buffer 35 is mounted on leaf spring 25. This device 35 is spaced slightly from spring 25 by means of a coiled spring 40 and is secured by a staple 41 which in turn has connection with the staple 42 passing in a transverse direction with reference to leaf spring 25 and extending therethrough. Staple coupling member 42 is threaded at its lower end and passes through a member 43 provided with longitudinal bores 44. Member 43 is disposed in an outer tube 45, the upper edges of which are flared as shown at 46. A nut 47 engages the threads of member 45 and a washer 48 provided with apertures 49 for the legs of the staple is located adjacent to said nut 47. Lock washers 50 are then placed around the ends of the staple or coupling member and are secured by nuts 51 provided with apertures for the reception of cotter pins 52. By this arrangement I provide an especially effective means for securing the buffers 35 which may receive the initial impact from the torpedo, said buffers having a practically universal movement.

The action of the members comprising the guard has already been described in connection with the description of the mechanical construction and it is believed that nothing further in that connection is required for the complete understanding of the device.

In Fig. 3, the relative position of the springs is shown under normal conditions and in Fig. 6, the position of the springs when under tension due to the impact of a torpedo is illustrated. In the figure last mentioned, it will be observed that the terminal spring or springs are thrown in such position that they constitute a buffering device for the adjacent pivoted devices 30 above mentioned.

While we have described the construction

of the device in considerable detail, we do not wish to be limited to the exact form specified, but may make such changes, alterations or additions as fall within the scope of the appended claims.

We claim:

1. In a device of the class described, a unit comprising a substantially rigid member for connection with the side of a ship, a plurality of pivoted members constituting buffers mounted within the rigid member, and resilient devices connecting said pivoted members.

2. In a device of the class described, a substantially rigid member to be mounted on the hull of a ship, a plurality of resiliently mounted and pivoted members connected with the rigid member, said pivoted members constituting buffers and having deflecting surfaces for engagement by a torpedo or the like.

3. In a device of the class described, a unit comprising a substantially rigid member for connection with the hull of a ship, a plurality of buffers pivotally mounted thereon, and resilient means for pivotally connecting the buffers, said buffers having torpedo deflecting surfaces.

4. In a device of the class described, a unit comprising a member to be mounted on the hull of a ship, a plurality of pivoted members mounted in said member first mentioned, resilient devices connecting the pivotally mounted members, and buffering devices mounted on certain of the resilient devices intermediate of the pivoted members first mentioned.

5. In a device of the class described, a unit comprising a plurality of buffers having torpedo deflecting surfaces, means for mounting said buffers and means for connecting said buffers permitting wave-like motion to be transmitted through a series of said buffers.

6. In a device of the class described, a unit comprising a plurality of buffers having deflecting surfaces, means for pivoting said buffers for swinging in given directions, resilient means connecting a plurality of buffers and transmitting motion thereto when placed under tension, and an additional buffering device mounted between certain of the buffers last mentioned and arranged to be deflected in any direction with reference to the main axis thereof.

7. In a device of the class described, a series of units arranged substantially parallel with reference to each other and comprising a series of buffers, certain of which are mounted to swing in a given direction with reference to the longitudinal axis of the buffer as a whole, resilient means for connecting the buffers, and additional buffers mounted to be deflected in any direction with reference to the longitudinal axis thereof.

8. In a device of the class described, a series of units comprising a plurality of channel members arranged substantially parallel with reference to each other and extending from a point near the water line of a ship's hull toward the keel thereof, said units comprising a plurality of buffers pivotally mounted, resilient members connecting said buffers and adapted to transmit motion thereto. 35
9. In a device of the class described, a unit comprising a channel member, abutments formed at the ends of the channel member, buffers pivotally mounted within said channel member, leaf springs connecting the buffers in a series and having connection with said abutments, and additional buffers mounted on certain of said springs and disposed between the buffers first mentioned. 40
10. In a device of the class described, a unit comprising a channel member, a buffering device mounted therein and arranged to swing laterally, said buffering device comprising an outer member having a torpedo deflecting surface, and a shank member for effecting connection with the channel member, and a spring mounted to retain said buffer in position under normal conditions, and to permit of the deflection of the buffer under impact. 45
11. In a device of the class described, a unit comprising a rigid member, a plurality 50
12. In a device of the class described, a unit comprising a channel member having cut-away portions near the ends thereof, abutments at the ends of the channel members, buffers comprising outer portions having deflecting surfaces and shank members pivoted to the channel, springs extending between the adjacent buffering devices and having pivotal connection with the shanks thereof at points spaced from the edges of the channel, certain of said springs having connection with the abutments and certain of the springs being adapted to carry mounting devices for additional buffers, and buffering devices mounted to swing in any direction with reference to their main axes, said buffering devices last mentioned being adapted to receive impact from a torpedo and to deflect said torpedo and simultaneously swing the adjacent buffers to a 55 position to further deflect said torpedo. 60

In testimony whereof we affix our signatures.

JOHN MORCH.
ANTHONY MORCH.
